CLAIM

The ornamental design for a portable light, substantially as shown and described.

DESCRIPTION

FIG. 1 is a perspective view of an ornamental design for a portable light;

FIG. 2 is a side view of a first side thereof;

FIG. 3 is a side view of a second side thereof;

FIG. 4 is a side view of a third side thereof;

FIG. 5 is a side view of a fourth side thereof;

FIG. 6 is an end view of a first end thereof;

FIG. 7 is an end view of a second end thereof.

FIG. 8 is a side view of the ornamental design for a portable light with a handle thereof pivoted to an alternate position of use away from the portable light.

FIG. 9 is a side view of the ornamental design for a portable light with a light head thereof pivoted to a first alternate position of use;

FIG. 10 is the side view thereof with the light head thereof pivoted to the first alternate position of use and rotated in a first alternate direction of use; and,

FIG. 11 is the side view thereof with the light head thereof pivoted to the first alternate position of use and rotated in a second alternate direction of use.

Broken lines in the Drawing indicate parts of the portable light that are not claimed and that form no part of the claimed design.

1 Claim, 9 Drawing Sheets
